(57) CLAIM

The ornamental design for a medicine cabinet, as shown and described.

DESCRIPTION

FIG. 1 is an isometric view of a medicine cabinet showing my new design;

FIG. 2 is another isometric view in an open configuration thereof;

FIG. 3 is a front elevational view thereof;

FIG. 4 is a rear elevational view thereof;

FIG. 5 is a left side elevational view thereof;

FIG. 6 is a right elevational view thereof;

FIG. 7 is a top plan view thereof; and,

FIG. 8 is a bottom plan view thereof showing my design. No claim is made to the floral pattern, pill cutter, and cup shown in broken lines, they are shown for illustration purposes only.

1 Claim, 6 Drawing Sheets
